THERMOSTAT

John S. Baker and Roy M. Schultz, Chicago, Ill.,
assignors to Cook Electric Company, Chicago,
Ill., a corporation of Illinois

Application March 14, 1938, Serial No. 195,732

25 Claims. (Cl. 200—139)

This invention relates to thermostats and is more particularly directed to a snap action thermostat.

Thermostats of the type herein disclosed are used largely in heating systems to control operation in accordance with ambient temperature changes in the space to be heated. They have been the subject of considerable development. Simple thermostats consisting of a contact member connected to or operated by a thermo-responsive element flutter when making and breaking contacts. This results in rapid deterioration of the contacts. To overcome this difficulty, magnets have been employed. The use of magnets in a thermostat is not satisfactory. They increase the cost and render it impossible to maintain accurately the calibration of the instrument, due to their strength changing with age. Furthermore, magnets collect particles of magnetic material which prevent closing of the contacts. On the other hand, spring mounted contacts have been used to secure a quick break or snap action of the movable contact without a fluttering movement. This type of device has met with much trouble thus far, largely due to construction and design. If a thermostat is not sturdily built and its parts are not designed and assembled to admit of easy and accurate calibration, and be capable of maintaining its temperature setting, the device necessarily has little practical value. One of the most serious difficulties heretofore experienced has been the inability of the construction to withstand rough handling during shipment. Quick loss of factory adjustment and the attendant difficulties of restoring it on the job have resulted in numerous replacements and consequent losses to the manufacturers.

An object of this invention resides, therefore, in the provision of a thermostat of the character described that is sturdy in construction, that may be easily assembled in the shop and readily calibrated to operate at predetermined temperature settings, that will retain such calibration during shipping and resist reasonably rough handling, that is exceedingly sensitive to temperature changes, and, although provided with a snap action element that may be actuated by a very light pressure, will effect maximum contact pressure at the moment of the break and thereby effect a quick and positive break between the contacts.

A further object of the invention is to provide in a thermostat of the character described, having the aforesaid characteristics, certain re-

finements in construction and operation that increase efficiency, sensitivity and reliability over a long period of time.

A still further object of the invention is to provide a construction that is sturdy and easily and effectively calibrated to operate at predetermined temperature settings with a high degree of sensitivity to temperature changes, the construction being simple and relatively inexpensive for its sensitive and reliable performance.

Primarily, the purpose of the invention is to provide a snap action thermostat of the character described that is practical and highly useful.

Specifically, a thermostatic element, preferably of bimetal and U-shape, is supported by a mounting that tends to urge the legs together in a manner giving a free-floating action but still urging one of the legs in a direction opposite to its direction of movement upon a temperature change to break the circuit. A bowed spring carrying a movable contact mounted upon said thermostatic leg is caused to remain under the tension of its bowing, which tension is progressively increased by the movement of this leg upon being influenced by a temperature change until maximum pressure (contact) is obtained at the moment the contacts are broken by a snap action. A manually adjustable member acting to modify the action of the mounting upon the thermostatic element is employed to predetermine the temperature settings at which the movable contact will be actuated by the thermostatic element to make or break the circuit. In order to calibrate the action of the various parts in their proper coordinating relation to operate to break or make contact at said predetermined temperature settings, means are provided that further modify the action of the manually adjustable member. The parts are arranged to secure great sensitivity of movement in order that the thermostatic element will quickly respond to changes in temperature. The structure is easy to assemble and adjust, and will keep its adjustment without difficulty.

A further object of the invention is preferably to provide the bimetallic element with its member of greater expansibility on the outside of the U so as to overcome any tendency of the bimetallic element to lose its adjustment during shipment if required to be subjected to abnormally low temperatures.

Other objects and advantages of the invention will be apparent from the following detailed ex-

planation when taken in connection with the accompanying drawings which form a part here-of.

In the drawings:

5 Figure 1 is a view of the device with the front cover removed;

Fig. 2 is an elevation of one side of the device but with the cover in cross section;

10 Fig. 2a is a detail elevational view of a portion of the cover;

Fig. 3 is a view similar to Fig. 2, but of the opposite side;

Fig. 4 is a front view of the base with the parts removed;

15 Fig. 5 is a section through the base taken on line 5-5 of Fig. 4, but with one of the terminal contacts in position;

Fig. 6 is a detail view of the thermostatic element;

20 Fig. 7 is a side view of one leg of the thermostatic element illustrating the bowed spring in side elevation;

Fig. 8 is a view of the bowed spring in its position when the movable contact engages the 25 cold contact;

Fig. 9 is a similar view but with the bowed spring in its opposite position with the movable contact engaging the hot contact;

Fig. 10 is an enlarged detail view illustrating 30 the movable contact on the bowed spring;

Fig. 11 is a detail view of the fixed stop member and stationary contact member at one side of the thermostatic element;

35 Fig. 12 is a similar view of the fixed stop member and stationary contact member at the opposite side;

Fig. 13 is a detail sectional view illustrating the position of the movable contact engaging the cold contact and the position of the bimetallic 40 leg (carrying this movable contact) engaging the fixed stop member that is in circuit with this cold contact; this relation of the parts being established by the action of the spring mounting of the bimetallic member urging its legs together;

45 Fig. 14 is a similar view illustrating the position of said parts after said action of the spring mounting to urge the bimetallic legs together has been modified by a manually adjustable member in order to set the device to make or break circuit at a predetermined temperature;

50 Fig. 15 is a similar view of these parts after the snap over action of the bowed spring, carrying the movable contact, has been effected by a change in position of the bimetallic element 55 through a change in temperature;

Fig. 16 is a similar view of these parts after the bimetallic leg has been moved to a position engaging the opposite fixed stop member by the manually adjustable member;

60 Fig. 17 is a similar view of these parts illustrating the bimetallic leg member after breaking contact with the fixed stop member and in a position to be influenced by a predetermined temperature change to actuate movable contact by a snap action to the opposite stationary contact member;

Fig. 18 is an enlarged detail sectional view illustrating the calibrating means;

70 Fig. 19 is a top plan view of the thermostat showing the cover partly in elevation but with the base of the device in section to illustrate the wall mounting plate;

Fig. 20 is a rear elevation of the thermostat illustrating the wall mounting member attached; 75 and,

Fig. 21 is a face view of this mounting member when secured to the wall.

Referring more particularly to the drawings, it will be noted that the thermostat comprises a base 1 that may be molded preferably of insulation material in any desired shape or form to carry the terminal connections and operating parts. A cover 2 is fitted over the front face and held by screws 3 extending from the vertical sides of the base. Cover 2 may be apertured at 4 on 10 each side and in the bottom to permit free circulation of air therethrough and may, if desired, carry a thermometer 5. Front face 6 of housing 2 may be slotted at 7 to receive a pointer 8 at the tip of a manually adjustable member 9 for cooperating with calibration markings 9' along the upper edge of slot 7.

To position the various terminals carried by base 1, raised faces 10, 11 and 12 may be molded upon the front face of base 1. To facilitate the 20 assembling of the terminals and their proper positioning upon base 1, ribs or projections 13, 14 and 15 may be formed. Terminal screws 16 and 17 are adapted to be threaded into bushings 19 from the rear side to provide connections for a two-wire circuit. The device may be adapted to a three-wire circuit through the use of a terminal screw 18, illustrated in Figs. 4 and 20. The specific type of connection may be varied, but there is illustrated in the specific form shown in the 30 drawings a bushing 19 that is internally threaded to receive screws 16, 17 and 18. Line connections may be made at the screw terminals 16, 17 and 18 from the rear face of base 1. An L-bracket 20 is secured by bushing 19 against rib 14. Projecting leg 21 of bracket 20 is apertured to receive a bolt 22' that receives and fastens the lower end of a mounting spring 22 to said bracket 20. The opposite end of mounting spring 22 is secured to one leg of a bimetallic member 23 of U- 40 shape whereby the latter is provided with a free-floating support, spring mounting 22 acting, however, to tilt both legs clockwise about bolt 22'. Bolt 22' rides in slot 24 (Fig. 5) in the lower end of spring mounting 22 which provides an adjustable connection permitting vertical adjustment of spring mounting 22, and, consequently, a similar adjustment of the bimetallic element 23.

The opposite side of the circuit represented by terminal screw 16 continues by means of a strap 50 25 held at one end upon raised face 11 by bushing 19 and at the other end upon raised face 12 by a similar connection. This connection also secures an L-bracket 26 upon raised face 12 against rib 15. A preheating element 27 is secured by bolt 28 to bracket 26 and lies adjacent one of the two legs 29 and 30 of bimetallic member 23 so as to influence the action of leg 29. The auxiliary heat supplied by member 27 anticipates the increased temperature that results from the 60 circuit being closed and the heater operating upon a demand of heat in the room or space in which the thermostat is located.

A portion of leg 29 is cut away at 32. A bowed spring 33 having a double reverse curve is secured at 34 and 35 to leg 29 to operate in this cut-away portion 32. A movable contact designated generally as 36 is mounted upon bowed spring 33 and is adapted to make and break contact between two oppositely arranged relatively stationary contacts 37 and 38. Brackets 39 and 40 carry stationary contact 37 and 38 in opposed but adjustable relation as shown, and are secured upon raised face 10 on opposite sides of projection 13. Terminal screw 18 is connected to bracket 40 so 75

that stationary contact 38 may be used, for example, as a hot contact or otherwise in the event the device is connected in a three-wire system. Brackets 39 and 40 are U-shaped and each is provided with outwardly extending legs, one of which 5 adjustably carries stationary contacts 37 and 38, while the other of which receives opposed relatively fixed stop members 41 and 42. Stationary contacts 37 and 38 are preferably disposed in the 10 same horizontal plane with fixed stop members 41 and 42. As shown more specifically in Figs. 11 and 12, upper U-bracket 40 has one short outwardly extending leg 43 (Fig. 12) with a depending slotted ear 44 and a long outwardly extending leg 45 (Fig. 11) with a depending ear 46 of substantially the same length. Fixed stop member 42 is adjustably carried in slotted ear 46 while relatively stationary contact 38 is adjustably carried in slotted ear 44. U-bracket 39 has similar 20 legs 47 and 48. Leg 47 has an upstanding slotted ear 49 that receives relatively stationary contact 37 and leg 48 has an upstanding slotted ear 50 that carries fixed stop member 41. Leg 48 is longer than leg 47. As a matter of fact, leg 45 25 of bracket 40 and leg 48 of bracket 39 are of the same length so that the fixed stop members 41 and 42 carried in slotted ears 46 and 50 will be in alignment with each other. Leg 43 and leg 47 of brackets 40 and 39, respectively, are of the 30 same length so that the relatively stationary contacts 37 and 38 will be in alignment with each other. In this connection, stationary contact 37 is in electrical relation with fixed stop member 41 because they are carried on the same bracket 35 39, leg 48 thereof receiving the upper end of the preheating element 27 at 52. Stationary contact 38 is in electrical relation with fixed stop member 42 because they are carried by bracket 40.

Leg 23 of the bimetallic element is adapted to 40 operate between fixed stop members 41 and 42, and, as will be presently explained, this leg 29 will break contact with either stop member before movable contact 36 on bowed spring 38 breaks contact with the stationary contact members 45 37 and 38. Likewise, leg 29 will make contact with either stop member 41 or 42 after movable contact 36 on bowed spring 38 makes contact with the stationary contact members 37 and 38, as will appear in the drawings (see Figs. 13 to 50 17, inclusive). The reduced portion of this leg 29, formed as the result of cutting away a part to provide a space in which bowed spring 33 operates, will move between fixed stop members 41 and 42 while bowed spring 33 with its movable 55 contact 36 will operate between said relatively stationary contact members 37 and 38. Bowed spring 33 is a strip of resilient or spring material formed into a double reverse curve as it is attached to leg 29 at 34 and 35 so that the stress 60 applied endwise will maintain the spring in the form of this double reverse curve. The limited movement of movable contact 36 operating between closely spaced stationary contact members 37 and 38 and the compressive force or stress applied endwise to bowed spring 33 keep, it is believed, this bowed spring in a state of unstable equilibrium, the resulting tension holding movable contact 36 under pressure against the stationary contact member that the latter engages. 65 For example, if movable contact 36 engages stationary contact member 37, leg 29 will be in a position toward or against the opposite fixed stop member 41 (see Figs. 13 and 14). A change of 70 temperature influencing bimetallic member 23 to move its leg 29 to the left will increase the ten-

sion of bowed spring 33 until a condition is reached where the increasing bending moment applied thereto causes it to disengage movable contact 36 from stationary contact member 37 with a snap action, this bowed spring thereby 5 moving in a direction opposite to the movement of leg 29. The increasing bending moment or stress imparted to spring 33 effects maximum contact pressure between movable contact 36 and stationary contact member 37 at the time of the 10 break. The switch operates substantially as an overcenter device but the spring 33 will remain in unstable equilibrium as movable contact 36 strikes and remains engaged against stationary 15 contact member 38.

Stating the action of the bimetallic member 23 and the bowed spring 33 differently, starting at any given point, the bimetallic member and the bowed spring are in a certain fixed position. Now, if the device is subjected to a temperature 20 change tending to cause it to move to opposite position, storage of energy in the bowed spring 33 will begin as well as a like amount of energy in the bimetallic member 23, which tends to drive the movable contact 36 carried by the 25 bowed spring 33 against the stationary contact which it is then engaging. When the energy stored in the bimetallic member 23 becomes sufficient to overcome the reaction of the bowed spring 33, the balance between the two is broken, the bimetallic member 23 moves forwardly 30 very rapidly and the bowed spring 33 simultaneously accelerates with extreme rapidity and moves in the opposite direction of the bimetallic 35 member.

In Figs. 8 and 9, both positions of bowed spring 33 are shown and the movable contact is designated generally as 36. Fig. 10 illustrates at an enlarged scale the construction of movable contact 36. Care must be exercised in shaping 40 movable contact 36 to prevent a molecular change in spring member 33. The contact is inserted through an aperture in bowed spring 33 and head 50 may be first formed. Care is then exercised to prevent striking the bowed spring 45 33 as head 51 is formed so as not to change the original characteristics of the spring material.

Manually adjustable member 9 carrying pointer 8 that registers with calibration markings 9' and rides in slot 7 in casing 2 is pivotally connected to base 1 at 55 by a screw that extends through the base and is held in position by nut 56 at the rear side. An abutment 57 is carried and operated by manually adjustable member 9 to engage upper end 58 of bimetallic leg 30 to 50 modify the action of spring mounting 22 and thereby predetermine the temperature setting at which the bimetallic element 23 will operate to make or break contact between movable contact 36 and the stationary contact members 37 and 38. As previously stated, spring mounting 22 functions to support bimetallic element 23 in free-floating relation and urges the same clockwise to bring leg 29 into engagement with the right-hand fixed stop 41 (see Fig. 13). As abutment 57 is pressed against upper end 58 of leg 30 by a left-hand pivotal movement of manually adjustable member 9 which raises abutment 57 upwardly to bring it against this upper end 58 of leg 30 and slide it therewith, bimetallic element 23 is tilted counterclockwise against the action of spring mounting 22. Leg 29 will thereby be moved to the left from engagement with right-hand fixed stop member 41 and the position it is given between fixed stop members 41 70 75

and 42 will determine the temperature setting of the device (see Fig. 14). Abutment 57 is secured to leg 59 of a right angular bracket including leg 60 that is adjustably attached to manually adjustable member 9. Leg 60 is slotted as indicated at 61 in Figs. 6 and 18, there being provided a struckup ear 62 that adjustably receives a screw 63 and has its end 64 bearing against the edge of manually adjustable member 9.

10 A bolt 65 is adapted to securely fasten leg 60 to manually adjustable member 9 (see Fig. 18.) Any suitable construction for securing this attachment may be provided. As shown, however, a boss 66 on manually adjustable member 9 is adapted to ride in slot 61 in leg 60, the parts being held together by bolt 65 threadedly engaging the disk 67 at the rear. Bolt 65 freely passes through a front washer 68 with its head recessed so as to lie flush with the face of washer 68.

20 Loosening bolt 65 permits relative movement so as to move bracket 60 laterally with respect to manually adjustable member 9. This adjusts the position of the abutment 57 with respect to its engagement with leg 30 of the bimetallic element 23. The construction described furnishes means for effecting proper calibration of the thermostat that is simply and easily made. After bolt 65 has been loosened to allow movement between leg 60 and manually adjustable member 9, screw 30 63 may be adjusted to move leg 60 to the right or to the left so as to increase or decrease the pressure exerted by abutment 57 against leg 30. An original calibration may be made in this manner by the adjustment described so that the leg 35 29 will be in a position with respect to fixed stop members 41 and 42 to move in either direction to make or break contact between movable contact 36 and stationary contact members 37 and 38 at a given temperature. For example, a calibration 40 may be made which will cause operation of the bimetallic member 23 at a given temperature. After this calibration is made, operation of the manually adjustable member will so modify the action of spring mounting 22 upon bimetallic element 23 as to adjust the position of leg 29 between fixed stops 41 and 42 as to cause operation at any desired temperature. If an original calibration is made through the means above described at a given temperature, say, 70° F., with 45 the pointer 8 registering with the corresponding calibration marking, as shown in Fig. 2a, the relation between abutment 57 and leg 30 is such that upon further movement or adjustment of manually adjustable member 9 to another temperature setting, the bimetallic element 23 will be in an adjusted position to operate at this new temperature setting to either make or break the contact.

Fig. 13 is a detail view specifically illustrating 60 the position of both bimetallic legs 29 and 30 and the movable contact 36 when manually adjustable member has been swung to the right to bring abutment 57 out of engagement with leg 30. The action of spring mounting 22 upon bimetallic element 23 to swing its both legs to the right or clockwise will be noted in this Fig. 13. Leg 29 is brought to bear against fixed stop 41 thereby exerting a bending moment upon bowed spring 33 to hold movable contact 36 against stationary contact member 37. The circuit will then be closed.

Fig. 14 illustrates a position of the various parts after manually adjustable member has been 65 swung to the left to bring abutment 57 against leg 30 so as to modify the action of spring mount-

ing 22 upon the legs of bimetallic element 23. This position may represent the position of the bimetallic element after a proper calibration has been made through adjusting screw 63 and its associated parts to cause operation of the bimetallic element at a predetermined temperature to actuate the bowed spring 33 for breaking circuit between movable contact 36 and stationary contact member 37. It will be noted that leg 29 has been moved to the left and out of engagement with fixed stop 41.

Fig. 15 represents the position of the various parts after a temperature change representing the predetermined setting previously given through the manually adjustable member 9. It 15 will be noted that leg 29 has been moved farther to the left and has caused bowed spring 33 to effect disengagement of movable contact 36 from stationary contact member 37 by a snap action. This will result in movable contact 36 engaging 20 stationary contact member 38. As stated, leg 29 has moved to the left. For the adjustment given and the change effected, as illustrated in Fig. 15, this leg 29 has not moved sufficiently to engage fixed stop 42. As the device is calibrated and 25 constructed to operate, the positioning of manually adjustable member 9 to the left provides predetermined temperature settings at lower temperatures. If the thermostat herein disclosed is employed in a three-wire system, say for example only, where stationary contact member 37 represents a cold contact operable when engaged by movable contact 36 to close a heating circuit during winter operation, the stationary contact member 38 may represent the hot contact in the 30 system for summer operation and may be used to close a circuit upon a rise of temperature instead of opening the circuit, as in the case of stationary contact 37. It will be understood that this illustration is given as one example of the 35 possible adaptation of the thermostat herein disclosed. Fig. 16 then represents the position of the parts when leg 29 engages fixed stop member 42, while Fig. 17 represents the position of the parts after the predetermined temperature setting 40 effecting operation of the thermostat at 45 higher temperatures as may be necessary in summer operation.

Figs. 13 and 14 illustrate that leg 29 will disengage fixed stop 41 before movable contact 36 50 disengages stationary contact member 37 while Figs. 16 and 17 illustrate that leg 29 will disengage fixed stop 42 before movable contact 36 disengages stationary contact member 38. The circuit is always broken by the snap action provided by bowed spring 33, and therefore, the slow make and break between leg 29 and fixed stops 41 and 42 are ineffectual to cause any sparking.

Thermostats are usually mounted on walls and are, therefore, apt to be influenced by the temperature of the wall rather than by the temperature of the surrounding air. Efficient operation of the thermostat will only be obtained if the arrangement prevents or minimizes wall temperature influence upon the thermostatic element. This advantage is obtained in the present disclosure by a wall plate 70 that is adapted to be attached directly to the wall and preferably lie within a recess 71 at the rear of base 1, which recess is formed by a flange 72 formed about the 70 periphery of base 1. Wall plate 70 is adapted to be mounted directly against the wall, as illustrated in Fig. 19. It is provided with a horizontal slot 73 at the top and a vertical slot 74 at the bottom. Mounting screws pass through these 75

slots and enter or otherwise are fastened to the wall, as indicated at 15. Vertical adjustment of wall plate 10 may be first obtained by means of vertical slot 14. The top screw may then be inserted through slot 14 and fastened in wall 15. Horizontal alignment to secure a true vertical position for the wall plate may be obtained by means of horizontal slot 13 before the screw is securely fastened. Spring fingers 16 and 17 are slotted, as illustrated, and fastened at 18 by rivets, or the like, to wall plate 10. The upper end of these spring fingers 16 and 17 are curved outwardly to be spaced from the wall plate whereby through the means of slots 19 the thermostat 15 may be attached to wall plate 10 by bringing headed studs 20 on base 1 into engagement with the slotted springs 16 and 17. The reduced shank of headed studs 20 may ride in slot 19 while the heads will lie between spring fingers and the wall 20 plate, but preferably without the heads touching the wall plate, thereby securely holding the thermostat against the wall and upon mounting plate 10, as shown in Figs. 3 and 19. Wall plate 10 may be made of metal. In order to reduce 25 conduction of heat between wall plate 10 and the thermostat, spacing lugs 21 are struck up at suitable points, say, at the corners of the central opening 22. These spacing lugs are of relatively small width, being somewhat V-shape and practically provide point contacts only with base 1, as illustrated at 23. Spacing lugs 21, therefore, hold base 1 away from wall plate 10 and provide an enclosed air space to act as insulation, it being noted that peripheral flange 22 of base 1 30 encloses this space and is brought into contact with the wall. Base 1 and therefore flange 22 is made of composition insulation material that is a low conductor of heat, and consequently, engagement of wall 25 by flange 22 will not materially affect the action of the thermostatic element 23 by any conduction of heat that may take place between this flange 22 and the mounting wall. Central opening 22 further advantageously permits ready connection of the circuit-wires to 40 such terminals as 16, 17 and 18 at the back of base 1. It will be apparent that wall plate 10 has numerous advantages and features in connection with mounting and holding the thermostat against a wall surface. The thermostat may be 45 removed at any time from against the wall without removing the wall fastening bolts, which, if removed a number of times might enlarge their openings in the wall and be loose therein. Moreover, the thermostat will not be influenced by a cold wall which often occurs and causes operation of the thermostatic member independently of any demand for heat that may be necessitated by air temperature in the room. It will further be observed that a space 26 might be provided between the edges of plate 10 and the peripheral flange 22 of base 1, and that the fit of the heads of studs 20 in slotted spring fingers 16 and 17 50 will not bring these heads in contact with plate 10 (see Figs. 3 and 19). Hence, an arrangement 55 may be obtained whereby the only contact between wall plate 10 and base 1 of the thermostat will be at 27 where the substantially narrow V-shaped spacing lugs 21 engage and firmly hold base 1 against wall plate 10 by practically point contacts.

It will be noted in Fig. 6 that outer member 28 of bimetallic element 23 is preferably of greater expansion than inner member 29. We find that such construction of a bimetallic member prevents any permanent rupturing of the parts by 75

the legs opening too far when the device is shipped unprotected into cold climates in winter.

From the foregoing description it will be observed that an improved thermostatic structure has been described that is exceedingly sensitive to temperature change but yet sturdy in construction to maintain its calibration. Moreover, the construction is of a character admitting of easy assembly of the parts and easy and rapid calibration by the workman. It avoids the heretofore difficult assembly problems of thermostatic structures and the possibility of inaccurate calibrations at the factory. The present device is of a character that necessarily provides accuracy of calibration at the time factory adjustments are made. This calibration is made at the room temperature at the time manually adjustable member 9 is moved to bring pointer 8 to the corresponding calibration marking 9'. Screw 65 is slightly loosened and screw 63 is then operated to move manually adjustable member 9 and consequently leg 29 until movable contact 36 breaks contact with relatively stationary contact member 37. Screw 65 is again tightened and the device is ready for use. Thus, the adjustment is very simple. In order for the thermostat to operate thereafter at different temperatures, manually adjustable member 9 is moved to bring pointer 8 to the corresponding calibration marking 9'. 30

The thermo responsive element is preferably in the form of a bimetallic member substantially of U-shape supported by a spring mounting that tends to press the legs together after one of the legs has been brought to bear against a fixed stop member. This said one leg is preferably provided with a bowed spring held under tension so as to be kept in unstable equilibrium whereby when this said one leg of the bimetallic member moves, the tension of the bowed spring increases and continues to increase until it snaps to another position whereby to break the circuit by a movable contact carried thereon. This arrangement of the bimetallic element and its spring support admits, therefore, of the adoption of a unique and efficient form of calibrating means that is simple and easy to operate, as explained above. 40

It will be kept in mind that one of the primary purposes of the present invention is to provide a practical, efficient and exceptionally sensitive 50 thermostat of the character described, which, in view of its accomplishments, is relatively inexpensive to manufacture.

Without further elaboration, the foregoing will so fully explain the gist of our invention that others may, by applying current knowledge, readily adopt the same for use under varying conditions of service, without eliminating certain features, which may properly be said to constitute the essential items of novelty involved, which items are intended to be defined and secured to as by the following claims. 60

We claim:

1. A thermostat comprising a substantially U-shaped bimetallic element having a movable contact on one of its legs, a relatively stationary contact on each side of said movable contact, a spring mounting for said bimetallic element to provide a free floating movement thereto, said mounting being secured to the opposite leg of said bimetallic element and tending to urge said legs together, and a member engaging said opposite leg for modifying the action of said mounting on said legs whereby to predetermine the operating temperature of said bimetallic element to 70 actuate said movable contact. 75

2. A thermostat comprising a substantially U-shaped bimetallic element having a movable contact on one of its legs, a relatively stationary contact on each side of said movable contact, a spring 5 mounting for said bimetallic element to provide a free floating movement thereto, said mounting being secured to the opposite leg of said bimetallic element and tending to urge said legs together, and a manually adjustable member for modifying 10 the action of said mounting on said legs to predetermine the operating temperature of said bimetallic element to actuate said movable contact.
3. A thermostat comprising a substantially U-shaped bimetallic element having a movable contact on one of its legs, a relatively stationary contact on each side of said movable contact, a 15 mounting for said bimetallic element tending to urge the legs thereof together, and means for modifying the action of said mounting on said legs to predetermine the operating temperature of said bimetallic element to actuate said movable contact, said means engaging the opposite leg of said bimetallic element beyond the point of connection of said mounting.
4. A thermostat comprising a substantially U-shaped bimetallic element having a movable contact on one of its legs, a relatively stationary member on each side of said movable contact, at 20 least one of said stationary members constituting a contact cooperating with said movable contact, a resilient mounting for said bimetallic element tending to urge its legs together, means for modifying the action of said mounting on said legs to predetermine the operating position of said contact legs between said stationary members, and calibrating means operable to calibrate the action of said modifying means to secure predetermined temperature settings of said bimetallic element 25 through the operation of said modifying means.
5. A thermostat comprising a substantially U-shaped bimetallic element having a movable contact on one of its legs, a relatively stationary member on each side of said contact, at least one of said stationary members constituting a contact 30 cooperating with said contact on said bimetallic leg, a resilient mounting for said bimetallic element tending to urge its legs together, and means for modifying the action of said mounting on said legs to predetermine the operating position of said contact leg between said stationary members, said means comprising a pivotally mounted manually 35 operable member and a bracket adjustably carried thereby for bearing against one leg of said bimetallic element.
6. A thermostat comprising a substantially U-shaped bimetallic element, a relatively fixed stop member on each side of one leg of said bimetallic element, a spring mounting for said bimetallic element urging said leg against one of said relatively fixed stop members, means for engaging 40 the opposite leg to oppose the action of said spring mounting whereby to adjustably shift said one leg to any predetermined position between said relatively fixed stop members, and calibrating means for said engaging means for predetermining a temperature setting at which said bimetallic element will operate to move said one leg.
7. A thermostat comprising a substantially U-shaped bimetallic element, a bowed spring carried by one leg of said element, a movable contact on said bowed spring, a relatively stationary member on each side of said movable contact, at least one of said stationary members constituting a contact 45 cooperating with said movable contact on said bowed spring, a relatively fixed stop member on each side of said leg, a spring mounting for said bimetallic element urging said leg against one of said relatively fixed stop members, and means for engaging the opposite leg to oppose the action of said spring mounting whereby to adjustably shift said one leg to any predetermined position between said relatively fixed stop members, and calibrating means for said engaging means for predetermining a temperature setting at which said bimetallic element will operate to move said one leg.
8. A thermostat switch for controlling an electric circuit comprising a substantially U-shaped bimetallic element having a movable contact on one of its legs, a bowed spring carried by said leg on which said movable contact is mounted, a relatively stationary contact on each side of said movable contact for causing said bowed spring to snap from one side to the other to effect a quick make and break of the circuit as said bimetallic element moves, a spring mounting for said bimetallic element to provide a free floating movement thereto, said mounting being secured to the opposite leg of said bimetallic element, and an adjustable member tending to spread said legs and provide thereby an adjustable thermostatic setting of said contact carrying leg with respect to said stationary contacts.
9. A quick acting thermostat comprising oppositely disposed relatively fixed stop members and oppositely disposed relatively stationary contact members, a thermostatic member operating between said stop members, a bowed spring carried by said thermostatic member, a movable contact on said bowed spring for engaging said stationary contact members, and means for urging said thermostatic member in either direction between said stop members whereby to increase the tension of said bowed spring and to secure thereby maximum contact pressure at the time said bowed spring snaps from one side to the other, said bowed spring moving oppositely in direction to said thermostatic member.
10. A quick acting thermostat comprising oppositely disposed relatively fixed stop members and oppositely disposed relatively stationary contact members, a substantially U-shaped bimetallic member having one of its legs operating between said stop members, a bowed spring carried by said bimetallic member and operating between said stationary contact members, a movable contact on said bowed spring for alternately engaging said stationary contact members, a mounting for said bimetallic member urging said operating leg against one of said stop members, and an adjustable member tending to modify said action of said mounting whereby to move said leg in the opposite direction, the movement of said leg in either direction increasing the tension of said bowed spring to secure maximum contact pressure at the time said bowed spring snaps from one side to the other, said bowed spring moving oppositely in direction to said bimetallic member.
11. A wall plate for mounting a thermostat comprising a substantially flat plate having a central cut-away portion, spacing lugs formed along the edges of said cut-away portion, and bifurcated fastening fingers adapted to receive fastening elements on the thermostat in slidable relation.
12. A thermostat comprising a bimetallic ele-

- ment having a contact movable therewith, a stationary contact, a resilient mounting for said bimetallic element tending to hold said movable contact against said stationary contact, and 5 means for modifying the action of said mounting tending to hold said movable contact against said stationary contact whereby to predetermine the operating temperature of said bimetallic element that will actuate said movable contact.
- 10 13. A quick acting thermostat comprising a thermostatic member having a contact movable therewith, a stationary contact, a mounting for said thermostatic member tending to hold said movable contact against said stationary contact, 15 a fixed stop against which said thermostatic member abuts when said movable contact engages said stationary contact, means for carrying said movable contact upon said thermostatic member to increase the contact pressure between 20 said movable contact and said stationary contact as said thermostatic member is influenced by a temperature change to move away from said fixed stop, and means for modifying the action of said mounting tending to hold said movable 25 contact and said thermostatic member against said stationary contact and said fixed stop whereby to predetermine the operating temperature of said thermostatic member to break contact between said movable contact and said stationary contact.
14. A quick acting thermostat comprising a thermostatic member, a mounting for said thermostatic member to provide a free floating movement thereto, a bowed spring carried by 30 said thermostatic member, a stationary contact, a contact on said bowed spring movable relative to said stationary contact, said mounting normally holding said bowed spring under compression with said movable contact engaging said 35 stationary contact, the formation of said bowed spring increasing the compression tension thereof as said thermostatic member is influenced by a temperature change, and means for modifying the action of said mounting whereby to predetermine the operating temperature of said 40 thermostatic element for breaking contact between said movable contact and said stationary contact.
15. A thermostat comprising a substantially 45 U-shaped bimetallic element, a contact movable with one of the legs of said bimetallic element, a relatively stationary member on each side of said movable contact, at least one of said stationary members constituting a contact cooperating with 50 said movable contact, a mounting for said bimetallic element urging both legs thereof in a given direction until said movable contact engages one of said stationary members and thereafter tending to urge both legs together, and means for modifying the action of said mounting on said legs to predetermine the operating temperature of said bimetallic element to actuate 55 said movable contact.
16. A thermostat comprising a substantially U-shaped bimetallic element, a contact movable with one of the legs of said bimetallic element, a relatively stationary member on each side of said movable contact, at least one of said stationary members constituting a contact cooperating with said movable contact, a mounting for said bimetallic element urging both legs thereof in a given direction until said movable contact engages one of said stationary members and there- 60 after tending to urge both legs together, means 65 for modifying the action of said mounting on said legs to predetermine the operating temperature of said bimetallic element to actuate said movable contact.
17. A wall mounting for a condition responsive device comprising, in combination, a base, condition responsive mechanism on said base, a wall plate, and means for detachably securing said base to said wall plate by a sliding movement of said base over and upon said wall plate, said means comprising projecting studs on the rear 70 face of said base and bifurcated members on said wall plate for receiving said projecting studs.
18. A wall mounting for a condition responsive device comprising, in combination, a base, condition responsive mechanism on said base, a rearwardly extending peripheral flange on said base adapted to rest against a wall on which said condition responsive device is to be mounted, a wall plate, a portion of said wall plate being cut-away to allow the passage of connections from said wall to the rear of said base, means for fixedly securing said wall plate in a predetermined position on said wall, means on said base for receiving said connections at the rear thereof, and means for detachably securing said base to said wall plate by a sliding movement of said base over and upon said wall plate after said connections have been attached to the rear of said base, said wall plate being enclosed by said peripheral flange.
19. A thermostat comprising a base, a temperature responsive element movable parallel to said base, a bracket on said base extending perpendicularly therefrom, a substantially flat resilient bar bent at both ends for attachment to said 40 bracket and said temperature responsive element, said bar providing a free floating resilient mounting for said temperature responsive element, the connection of said bar at said bracket including a fastening member carried by said bracket and 45 a slot in said bar for receiving said fastening member in adjustable relation.
20. A thermostat comprising a base, a bimetallic strip bent intermediate its ends to form an elongated U-shaped member disposed upon said base, 50 means for mounting said bimetallic strip including a bracket secured to said base and having an arm extending perpendicularly therefrom, a resiliently formed bar having one end secured to one leg of said bimetallic strip and the other end slotted for connection to said bracket arm in adjustable relation, and a manually operable member having a surface movable against said leg of said bimetallic strip to modify the resilient action of said mounting bar.
21. A thermostat comprising a base, a substantially U-shaped bimetallic element, mounting means for said bimetallic element, said mounting means connecting one leg to said base to provide a free floating movement to said bimetallic element and cause ambient temperature changes to affect the position of the opposite leg, said opposite leg having a portion thereof cut away, a bowed spring suspended across said cut-away portion and secured to said leg to move therewith, a contact on and movable with said bowed spring, stationary contacts on opposite sides of said spring contact, said movable contact operating to swing with said bowed spring to opposite sides of said leg through its said cut- 75

a-way portion to effect a sensitive quick make and break with said stationary contacts.

22. A thermostat comprising a bimetallic element having a contact movable thereby, means for tiltably mounting said bimetallic element, and adjusting and calibrating means for predetermining the operating temperature of said bimetallic element to operate said movable contact comprising a swinging lever and an abutment mounted thereon for engaging and modifying the tilttable position of said bimetallic element, the mounting of said abutment including a member normally locked to said swinging lever and means for moving said member relative to said swinging lever when in an unlocked condition whereby to adjust the pressure of said abutment against said bimetallic element.

23. A thermostat comprising a bimetallic element having a contact movable thereby, means for mounting said bimetallic element so that a tilting movement about said mounting means when said bimetallic element is influenced by temperature changes will operate said movable contact, and calibrating means for predetermining the operating temperature of said bimetallic element to actuate said movable contact comprising a swinging lever, a bracket movably carried on said lever, means movable by said bracket for engaging said bimetallic element, and a calibrating member carried by said bracket and engaging said lever to adjust the position of said bracket relative to said lever.

24. A thermostat comprising a bimetallic element having a contact movable thereby, means for mounting said bimetallic element so that a tilting movement about said mounting means when said bimetallic element is influenced by

temperature changes will operate said movable contact, and calibrating means for predetermining the operating temperature of said bimetallic element to actuate said movable contact comprising a swinging lever, a bracket movably carried on said lever, means movable by said bracket for engaging said bimetallic element, and a calibrating member carried by said bracket and engaging said lever to adjust the position of said bracket relative to said lever, and means for normally locking said bracket against the action of said calibrating member.

25. A quick acting thermostat comprising oppositely disposed relatively stationary members, at least one of which is a contact member, a thermostatic element having a contact movable thereby for operating between said stationary members, a bowed spring under tension mounted upon said thermostatic element to carry said movable contact, oppositely disposed relatively fixed stops for limiting the movement of said thermostatic element, both said fixed stops and said stationary members being spaced a distance apart from each other respectively to hold said bowed spring in unstable equilibrium when said movable contact is against either one of said stationary members, and means for normally urging said thermostatic member against one of said fixed stops whereby movement of said thermostatic member away from the said fixed stop by a temperature change will increase the energy stored in said bowed spring to secure maximum contact pressure at the moment of breaking engagement of said movable contact.

JOHN S. BAKER.
ROY M. SCHULTZ.

CERTIFICATE OF CORRECTION.

Patent No. 2,222,062.

November 19, 1940.

JOHN S. BAKER, ET AL.

It is hereby certified that error appears in the printed specification of the above numbered patent requiring correction as follows: Page 5, second column, line 62, for the word "as" read --us--; page 7, first column, line 41, claim 14, strike out "tension"; and that the said Letters Patent should be read with this correction therein that the same may conform to the record of the case in the Patent Office.

Signed and sealed this 14th day of January, A. D. 1941.

(Seal)

Henry Van Arsdale,
Acting Commissioner of Patents.
